UNITED STATES PATENT OFFICE.

JAMES E. HUNT, OF CHICAGO, ILLINOIS.

BARBED FENCE-WIRE.

SPECIFICATION forming part of Letters Patent No. 338,229, dated March 16, 1886.

Application filed May 8, 1885. Serial No. 164,826. (No model.)

To all whom it may concern:

Be it known that I, JAMES E. HUNT, of Chicago, in the county of Cook and State of Illinois, have invented a new and Improved 5 Barbed Fence-Wire, of which the following is a full, clear, and exact description.

The object of my invention is to provide a new and improved barbed fence-wire in which the barbs are held on a single wire as firmly 10 and securely as they are held on twisted wires.

The invention consists in the peculiar construction and arrangement of parts as hereinafter fully described, and pointed out in the claim.

15 Reference is to be had to the accompanying drawing, forming a part of this specification, in which a perspective view of my improved fence-wire is shown.

The plain fence-wire A is provided with the 20 loop B, which is slightly contracted at its open end. The wire C, having its ends pointed or beveled off to form the barbs, is passed through the loop B, and is wrapped one or more times around the loop, the pointed ends projecting 25 in opposite directions. Thereby the wire C is held securely on the wire A as well as it is held on a twisted wire.

By fastening the barbed wires in the manner set forth they can be held on a single wire.

I am aware that a barb consisting of a piece 30 of wire bent into the form of a figure 8, with its ends projecting in opposite directions and secured upon a bent wire, is old; and I am also aware that a barb consisting of two pieces of wire has been secured to a wire with a bend 35 in it by wrapping said pieces of wire around the bend at right angles to each other, so as to interlock and securely hold them to the wire, with their ends projecting outward, and I therefore do not claim such inventions. 40

Having thus fully described my invention, I claim as new and desire to secure by Letters Patent—

The combination, with the wire A, provided with the loop B, having its open end contracted, 45 of the wire C, wrapped around the loop with its ends projecting in opposite directions and having one end projecting through the said loop, substantially as herein shown and described.

JAMES E. HUNT.
